(57) **CLAIM**

The ornamental design for a food cooking device, as shown.

DESCRIPTION

FIG. 1 is a perspective view of the design for a food cooking device in accordance with a preferred embodiment of the present invention;

FIG. 2 is a front view of the food cooking device of FIG. 1, the rear view being identical to the front view;

FIG. 3 is a right side view of the food cooking device of FIG. 1, the left side view being identical to the right side view;

FIG. 4 is a top view of the food cooking device of FIG. 1; and,

FIG. 5 is a bottom view of the food cooking device of FIG. 1.
